UNITED STATES PATENT OFFICE.

GUSTAVE A. JOHNSON, OF NEWARK, NEW JERSEY.

METALLIC MOLDING.

1,141,188.

Specification of Letters Patent. Patented June 1, 1915.

Application filed May 12, 1913. Serial No. 766,941.

To all whom it may concern:

Be it known that I, GUSTAVE A. JOHNSON, a citizen of the United States, residing at Newark, in the county of Essex and State of New Jersey, have invented certain new and useful Improvements in Metallic Molding; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

15 The present invention has reference, generally, to improvements in metal molding which serves to provide a conduit for carrying electric circuit wires, and which may be connected with the ceiling of rooms, or 20 mounted upon the side walls of a room so as to provide, in addition to its wire carrying function, a means for supporting pictures and other decorative or ornamental articles upon the said walls.

25 The present invention has for its principal object to provide a cheap, simple and complete two-piece metallic hollow molding, for the purpose above mentioned, which can be made in suitable lengths, the same comprising a body-portion and a cover-portion in 30 possession simple and integrally formed means for joining the one with the other in their properly assembled relation. The said cover-portion being easily removable or detachable from said body-portion so that access to the interior of the molding and the 35 electric wires contained therein may be quickly and easily attained at all times without danger of injuring the walls or ceilings 40 to which the molding is attached.

Another object of the invention is to provide a metallic molding of the character described, which is of neat appearance, and which offers a fire-proof inclosure for supporting and concealing the electric circuit 45 wires adapted to be contained therein.

The present invention consists, therefore, in the novel features of construction and the novel combinations and arrangements of the 50 various parts of the hollow metal molding hereinafter more fully described in the accompanying specification and illustrated in the accompanying drawings, and then finally embodied in the clauses of the claim which is 55 appended to and which forms an essential part of the said specification.

The present invention is clearly illustrated in the accompanying drawings, in which:

Figure 1 is a face view of the novel construction of metal molding made according to the principles of my present invention, the cover portion of the same being shown in its closed or attached relation to the body-portion thereof; Fig. 2 is a transverse section of the same; and Fig. 3 is a similar 65 transverse section with the cover-portion shown in detached relation to said body-portion, but in a position about to be snapped or sprung into closed or connected relation therewith.

70 Similar characters of reference are employed in all of the above described views, to indicate corresponding parts.

Referring now to the accompanying drawings the reference character 1 indicates a 75 back-plate forming a part of the body-portion, said back-plate being provided with suitably disposed perforations 2 through which may be passed the holding or fastening screws 3, whereby said body-portion is 80 secured upon a wall or ceiling 4 in operative position. The lower portion of said back-plate is bent forwardly and upward to provide a U-shaped portion 5, thus forming a longitudinal trough or chamber 6 in which 85 may be concealed and supported electric circuit wires 7, as shown. The free edge of said U-shaped portion is turned or bent slightly forward to provide a holding rim 8. The upper portion of said back-plate 1 90 is bent forward and downward to provide a receiving-bead or holding-member 9.

95 The reference character 10 indicates a cover-member adapted to be detachably connected with said body-portion to close the same, thereby completely enveloping the electric circuit wires 7. The upper longitudinal edge 11 of said cover-member is adapted to be received and engaged in said receiving-bead or holding-member 9 of said 100 body-portion. The lower end of said cover-member is provided with a forwardly extending portion 12 adapted to register above and close over the open end of said U-shaped portion 5 of said body-portion. Connected 105 with the outer or free longitudinal edge of said forwardly extending portion 12 is a receiving-bead 13 which is adapted to be sprung or snapped into holding engagement with said holding-rim 8, whereby said cover-member is retained in closing relation to said body-portion.

It will be apparent from the above detailed description that the present invention provides a very simple two-piece metallic molding easily mounted and of neat appearance, and, furthermore, that the body-portion thereof provides a means for supporting electric-wires, which cannot fall from their supported relation when the cover-portion is removed, and when the cover-portion is in closing position said wires are entirely enveloped and concealed.

I am aware that some changes may be made in the various arrangements and combinations of the parts, particularly with reference to their shape or conformation, hence I do not limit my invention to the exact arrangements and combinations of the various parts or to the exact details of said parts as above described and illustrated in the accompanying drawings, except as the same may be limited by the scope of the claim appended hereto.

I claim:—

A metallic molding comprising a back-plate having suitably disposed perforations for the insertion therethrough of fastening

screws, a U-shaped portion providing a trough connected with the lower edge of said back-plate and extending longitudinally throughout the length of the latter, the free edge of said U-shaped portion having an outwardly bent lip providing a holding-rim, the upper edge of said back-plate being bent forward and downward to provide a female receiving-bead, a removable cover-member the upper marginal edge of which is adapted to be received in said female receiving-bead, a female holding-bead connected with the lower marginal edge of said cover-member adapted to be sprung over said holding-rim of said U-shaped portion to retain said cover-member in closing relation to said trough formed by said U-shaped portion.

In testimony, that I claim the invention set forth above I have hereunto set my hand this 10th day of May, 1913.

GUSTAVE A. JOHNSON.
